RAM HEAD

Karl O. Nelson, Milwaukee, Wis., assignor to
Galland-Henning Manufacturing Company,
Milwaukee, Wis.

Application July 15, 1933, Serial No. 680,597

6 Claims. (Cl. 100—29)

This invention appertains to presses and more particularly to a novel ram head for baling presses.

In presses of the high compression type, considerable difficulty is often encountered in returning the ram head to its normal position after the completion of its working stroke, in that the material being compressed works in between the press box and ram head and causes an obstruction commonly known as a fin. This fin has to be, in numerous instances, severed by the use of tools, such as chisels and the like. It has been proposed to eliminate the formation of the fin by providing the walls of the press box and the sides of the ram head with mating ribs and grooves. This prevents the formation of the fin under certain conditions, but where the fin is formed with this construction, the cutting off of the fin is rendered more difficult by the ribs and grooves.

It is therefore one of the primary objects of this invention to provide novel means for constructing the ram head itself, whereby the head is permitted to give or collapse on its return stroke and to ride over or past the fin.

Another salient object of my invention is the provision of a self-releasing ram head having its working face provided with wear plates which normally project beyond the sides of the ram head proper and which form a solid abutment against the head upon the forward working stroke of the head, but which are permitted to give inwardly upon the return of the head.

A further important object of my invention is to provide a ram head having sectional wearing plates on its working face, the meeting edges of the sections of the wear plates being bevelled in opposite directions, whereby the plates are permitted to give inwardly and forwardly upon the return movement of the ram head, the sections of the wear plates normally resting firmly against the head upon the forward movement of the ram.

A further object of my invention is the provision of novel means for connecting the wear plates with the ram head, whereby said plates will be normally held in proper position on the head, said means including bolts carried by the plates and loosely extending through the ram head with resilient means on the bolts normally urging the plates into contact with the head.

A still further object of my invention is to provide an improved ram head for baling presses of the above character, which will be durable and efficient in use, one that will be simple and easy to manufacture and one which can be placed upon the market at a reasonable cost.

With these and other objects in view, the invention consists in the novel construction, arrangement and formation of parts, as will be hereinafter more specifically described, claimed

and illustrated in the accompanying drawing, in which drawing:

Figure 1 is a front elevation of a ram head constructed in accordance with my invention.

Figure 2 is a side elevation of the same showing parts thereof broken away and in section to illustrate structural detail.

Figure 3 is a front elevation illustrating a slightly modified form of my improved frame, one of the wear plates being shown broken away to illustrate the novel construction of said plates.

Figure 4 is a side elevation of a ram head showing a still further form thereof.

Referring to the drawing in detail, wherein similar reference characters designate the corresponding parts throughout the several views, the letter A generally indicates my improved ram, which comprises the head 5 connected in any preferred manner to the ram plunger 6. The ram head 5 can be of any preferred construction and reinforced in any desired manner and the same embodies a solid front body 7.

The forward working face of the solid body 7 is provided with my novel wear plates 8, 9 and 10. The wear plate 9 is disposed at the longitudinal center of the body 7 and extends entirely across the same and is rigidly secured to the ram head by the use of fastening elements 11. The longitudinal edges of the central wear plate 9 is bevelled in opposite directions as at 12 for a purpose, which will be later set forth. The side wear plates 8 and 10 likewise extend across the face of the ram head and the same have their inner longitudinal edges bevelled inwardly as at 13, and these bevelled edges 13 rest upon bevelled faces 12 of the central wear plate 9.

As clearly shown in Figure 2 of the drawing, the outer edges of all of the wear plates 8, 9 and 10 extend beyond the perimeter of the body and thus, these projecting edges of the wear plates engage the inner faces of the press box (not shown).

Rigidly secured to the wear plates 8 and 10 are rearwardly extending bolts 14 and these bolts extend loosely through enlarged openings 15 formed in the ram head. Surrounding the bolts 14 are relatively heavy expansion springs 16 which bear against the rear face of the body 7 of the ram head and against adjusting nuts 17 on said bolts.

The ram head illustrated in Figures 1 and 2 is adapted for use in certain types of presses wherein two of the walls of the press box are immovably disposed and thus, the ram head is adapted to give only in two directions. In use, upon forward movement of the ram all of the wear plates rest solidly against the body 7 of the ram head and thus, the formation of the wear plates does not detract from the operation of the ram head upon its forward movement. Upon rearward

movement of the ram head, should an obstruction be met, such as the fins heretofore referred to, the plates 8 and 10 will be permitted to slide inwardly toward one another against the tension 5 of the coil springs 16. As lateral pressure takes place on the outer longitudinal edges of the wear plates 8 and 10, these plates will be forced inwardly and outwardly and the bevelled faces 12 and 13 act as a guide means for said wear plates. As soon 10 as the obstruction is passed, the plates will be returned to their normal position by the springs 16 and the arrangement of said bevelled faces 12 and 13.

In Figure 3 I have illustrated a ram head where- 15 in the wear plates can give in all four directions and this head is particularly adapted for use in baling presses, wherein all of the walls of the press box are of an immovable nature.

In this form of my invention, I utilize four 20 wear plates 20, 21, 22, and 23 and these plates each occupy substantially a one-fourth part of the front of the ram. Each plate is provided with a single rearwardly extending bolt 24 which extends through the ram head in the same manner as that shown in Figure 2 of the drawing and these bolts are also spring pressed.

The section or wear plate 20 has its two inner edges inwardly bevelled, as shown in Figure 3. The section 21 has one edge bevelled outwardly 30 as at 25 and this edge engages the inwardly bevelled facing edge of the section or wear plate 20. The other edge of the wear plate 21 is inwardly bevelled as shown. The wear plate 22 has one inner edge bevelled as at 26 and this edge 35 engages the other inwardly bevelled edge of the wear plate 20. The other inner edge of the wear plate 22 is inwardly bevelled as shown. The wear plate 23 has both of its inner edges outwardly bevelled for engaging the inwardly bevelled edges 40 of the sections or wear plates 21 and 22.

In operation of this type of ram head, it can be seen that the wear plates act to release or collapse in all four directions and upon the return stroke of the ram, the plates are enabled to give 45 inwardly owing to the formation of their meeting edges and the means of mounting the same on the ram head. All of the plates tend to resume their normal position as soon as the fin is passed due to the thrust of the expansion 50 springs, and the bevelled faces slide one on the other to guide said plates back to their original places.

Obviously, my self-releasing ram head is open 55 to various modifications and in Figure 4 I have shown still another form.

In this view I provide two wear plates indicated by the reference characters 27 and 28. These wear plates extend entirely across the face of the ram head and each occupies substantially 60 one-half of the area of the forward face of said head. The meeting edges of the wear plates 27 and 28 are bevelled in opposite directions as indicated by the reference characters 29 and 30 and these bevelled faces engage one another as 65 clearly shown in Figure 4. The plates carry the bolts 31 on which are mounted the expansion springs 32. The opposite ends of the springs bear respectively against the ram head and adjusting nuts 33 threaded on said bolts. This type of ram head operates in substantially the same manner 70 as the first form of my ram illustrated in Figures 1 and 2.

From the foregoing description, it can be seen 75 that I have provided an exceptionally simple and durable form of ram head which will permit the

ram head to return to its normal position irrespective of the formation of fins or the like on the material being compressed.

Changes in details may be made without departing from the spirit or the scope of this invention, but what I claim as new is:

1. A self-releasing ram head for baling presses comprising a rigid body, sectional wear plates arranged at the front end of the body, guide posts carried by the wear plates loosely extending through the body, whereby the sections of the wear plate are free to swing on the body upon movement of the body in one direction, and spring means normally urging the sections into intimate contact with the inner face of the body. 15

2. A self-releasing ram head for baling presses comprising a rigid body, sectional wear plates at the front end of the body, bolts carried by the sections of the wear plates extending loosely through the body, spring means on said bolts 20 normally urging the sections into intimate contact with the forward face of the body, the meeting edges of the sections being provided with companion mating bevelled faces.

3. A self-releasing ram head for baling presses 25 comprising a rigid body, a centrally disposed wear plate extending across the front face of the body and rigidly secured thereto, the longitudinal edges of the wear plate being bevelled in opposite direction, and side wear plates extending across 30 the front face of the body having their inner longitudinal edges bevelled for sliding engagement with the bevelled edges of the first wear plate, rigid bolts carried by the side wear plates extending loosely through the body, and expansion 35 springs normally holding the side wear plates flat against the front face of the body.

4. A self-releasing ram head for baling presses comprising a rigid body, wear plates arranged at the front of the body, each of said plates occupying substantially a one-fourth of the area of the front of the body, means loosely mounting each plate on the body, spring means normally urging each of the plates into intimate contact with the front of the body, one of said plates 45 having its inner edges bevelled inwardly, another of said plates having its inner edges bevelled outwardly, and disposed diagonally opposite the first plate, and the other two of said plates having one of their inner edges bevelled outwardly and 50 the other of their inner edges bevelled inwardly, said bevelled edges of the wear plates being disposed in overlapping relation, as for the purpose specified.

5. A self-releasing ram head comprising a body, 55 independent wear plates fitted against the forward face of the body having oppositely bevelled, overlapping meeting edges for camming engagement with each other, and means loosely mounting at least one of said plates on the body whereby upon forward movement of the head the plates will be forced into solid engagement with the body, and upon rearward movement of the head independent movement between the plates will 65 be had.

6. A self-releasing ram head comprising a body, independent wear plates mounted upon the forward end of the body having oppositely bevelled, overlapping meeting edges constituting camming 70 means therebetween, means loosely mounting at least one of said plates on the body, and spring means normally urging the loosely mounted plate flat against said body.
